UNITED STATES PATENT OFFICE.

ALBERT V. CULVER AND WILLIAM A. WADDELL, OF FRANKFORT, INDIANA.

WEATHER STRIP.

1,424,283.

Specification of Letters Patent. Patented Aug. 1, 1922.

Application filed December 13, 1921. Serial No. 522,041.

To all whom it may concern:

Be it known that we, ALBERT V. CULVER and WILLIAM A. WADDELL, citizens of the United States, residing at Frankfort, in the 5 county of Clinton and State of Indiana, have invented certain new and useful Improvements in Weather Strips, of which the following is a specification.

This invention relates to weather strips 10 for windows, doors and the like, and particularly to structures known as "French" windows, and is an improvement over that form of device shown in the patent to Albert V. Culver, issued October 5, 1920, No. 15 1,354,729. The prime feature of the present invention is the provision of a combined lock and weather strip operating mechanism so constructed that when the bolt of the lock is moved to open or closed position 20 the weather strip will be moved to inoperative or operative position, thereby obviating the possibility of the window or other swinging structure being opened while the weather strip is still in operative position. 25 A further feature of the invention is in so operating the weather strip co-incident to the locking of the bolt that the weather strip will be elevated above the sill of the window just prior to the releasing of the 30 bolt from its locking socket.

A further feature of the invention is the provision of means for causing the weather strip to extend in a horizontal position when in full open or closed position.

35 And a further feature of the invention is the provision of a shield or housing for the weather strip.

Other objects and advantages will be hereinafter more fully set forth and pointed 40 out in the accompanying specification.

In the accompanying drawings,

Figure 1 is an elevation of a window structure with the weather strip applied to use,

45 Figure 2 is an enlarged detail sectional view through the lower portion of the window structure and the sill showing the parts in locked position,

Figure 3 is a detail sectional view as seen 50 on line 3-3 Figure 2,

Figure 4 is a detail sectional view as seen on line 4-4 Figure 3, and

55 Figure 5 is an enlarged elevation of the weather strip showing parts broken away and parts by dotted lines.

Referring to the drawings, 1 indicates a

window frame, and 2 indicates a sash or window structure secured thereto in the usual manner which may be either along the top edge of the sash or at one end thereof. 60 The lower bar 3 of the sash co-operates with a ledge 4 of a sill 5, the bar 3 registering with the ledge when the sash is in closed position.

Window sash of this construction swing 65 inwardly and considerable difficulty has been experienced in preventing rain and the like from entering between the bar 3 of the sash and the ledge 4, and to overcome this objectionable feature, a weather strip 70 6, preferably of sheet metal, is extended transversely of the sash over the outer face of the bar 3, said weather strip, when in lowered position, extending a distance below the upper edge of the ledge 4, consequently preventing the passage of air, rain, 75 or the like, between the sash and sill.

In the present construction, the shank 7, employed for operating a locking bolt 8, is also employed for raising and lowering 80 the weather strip 6, the shank 7 being in the form of a pinion which co-operates with a rack 9 on the locking bolt 8, so that when the shank is rotated in one direction the bolt will be raised, and when rotated in the opposite direction will descend and enter a socket 10 formed in the ledge 4, the locking bolt 8 being slidably mounted in a sleeve 11 which is entered in an orifice in the bar 3. 85

The shank 7 is extended a distance beyond the bolt 8 and projects into an elongated slot 12 formed through a plate 13 attached to the inner face of the weather strip 6, one edge wall of the slot 12 having a rack 14 thereon for co-operation with the 90 teeth of the shank 7. The shank 7 is extended horizontally through the bar 3 and has attached to its outer end a knob 15 so that the shank may be readily rotated. The plate 13 is attached at the longitudinal center of the weather strip 6, and to cause the weather strip to rest in a horizontal plane when in its lowered or elevated position, elongated guide slots 16 are formed through the weather strip 6 at points on opposite 100 sides of the plate 13, and through these guide slots are extended guide pins 17 which are entered into the face of the bar 3.

To protect the weather strip from sleet and ice and other weather inclemencies, 110 which would tend to prevent operation of the strip, a shield or housing 18 is attached

to the outer face of the bar 3 so as to completely cover the weather strip when in inoperative position, and which protects the upper portion of the weather strip when in 5 its operative position.

The weather strip 6 is so arranged with respect to the bolt 8 that the lower edge of the weather strip will be moved upwardly until entirely free of the ledge 4 before the 10 lower end of the locking bolt entirely leaves the socket 10, consequently the sash cannot be moved inwardly until the weather strip is entirely removed from the path of the ledge, hence there is no possibility of injuring the 15 weather strip by directing an inward pull on the sash.

Furthermore, by raising and lowering the locking bolt and weather strip from the same source and at the same operation, it 20 will be impossible to operate the bolt without operating the weather strip, thereby rendering the structure substantially fool proof. It will likewise be seen that this device may be very easily and quickly attached to the 25 sash and will be practically indestructible from use in view of the simplicity of the device, and the few parts required in constructing the same.

Having thus fully described our said invention, what we claim as new and desire to secure by Letters Patent, is:

1. The combination with a locking bolt for a swinging closure, said bolt having teeth thereon, of a weather strip movably mounted upon the closure, said strip having teeth thereon, and a toothed operating shank cooperating with the teeth of said bolt and strip for raising or lowering both the locking bolt and weather strip simultaneously.

40 2. The combination with a locking bolt for swinging closures having rack forming teeth thereon, and means for slidably mounting the locking bolt in the swinging closure, of a weather strip removed from said locking bolt, rack forming teeth on the weather strip, and a single shank for simultaneously engaging the rack forming teeth of both the locking bolt and weather strip for operating said bolt and weather strip in unison.

50 3. The combination with a locking bolt for swinging closures having rack forming teeth thereon, and a shank having pinion forming teeth for operating said bolt when rotated, of a weather strip along one face of the swinging closure, a slotted plate connected with said weather strip and having rack forming teeth for co-operation with the

pinion forming teeth of said shank, whereby said locking bolt and weather strip will be operated in unison upon rotation of said 60 shank.

4. The combination with a locking bolt for swinging closures, rack forming teeth on said bolt, and a shank having pinion forming teeth for co-operation with the rack 65 forming teeth for operating the locking bolt when the shank is rotated, of a weather strip associated with one face of the swinging closure, and rack forming teeth carried by the weather strip for engagement with the pinion forming teeth of the shank whereby said locking bolt and weather strip will be operated in unison upon rotation of said 70 shank.

5. The combination with a locking bolt 75 for swinging closures, rack forming teeth on said bolt, and a shank having pinion forming teeth for co-operation with the rack forming teeth for operating the locking bolt when the shank is rotated, of a weather strip 80 associated with one face of the swinging closure, rack forming teeth carried by the weather strip for engagement with the pinion forming teeth of the shank, whereby said locking bolt and weather strip will be 85 operated in unison upon rotation of said shank, and means for normally maintaining the weather strip in horizontal position.

6. The combination with a locking bolt 90 for swinging closures, rack forming teeth on said bolt, and a shank having pinion forming teeth for co-operation with the rack forming teeth for operating the locking bolt when the shank is rotated, of a weather strip 95 associated with one face of the swinging closure, rack forming teeth carried by the weather strip for engagement with the pinion forming teeth of the shank, whereby said locking bolt and weather strip will be 100 operated in unison upon rotation of said shank, means for normally maintaining the weather strip in horizontal position, and a shield for forming a housing for the weather strip.

In witness whereof, we have hereunto set 105 our hands and seals at Indianapolis, Indiana, this 5th day of December, A. D. nineteen hundred and twenty-one.

ALBERT V. CULVER. [L. S.]
WILLIAM A. WADDELL. [L. S.]
